TUBE SQUEEZER

Boyce J. Oliver, Jacksonville, Fla.

Application October 2, 1942, Serial No. 460,567

3 Claims. (Cl. 222—102)

This invention relates to a tube squeezer especially adapted for dispensing the contents of collapsible tubes, and has for the primary object the provision of a device of the above stated character which will be extremely simple and easy to handle and will permit a person to dispense the contents of the tube directly on a surface in amounts as needed without waste and provides an efficient holder for the tube to prevent loss or misplacement thereof when not in use and may be handled and operated similarly to a pistol wherein the actuation of the trigger thereof controls the dispensing of the contents.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which

Figure 1 is a side elevation illustrating a tube squeezer constructed in accordance with my invention, and showing the device supporting and acting on a collapsible tube.

Figure 2 is a top plan view partly in section illustrating the device.

Figure 3 is a transverse sectional view illustrating the pressure rollers and the means of operating said rollers.

Figure 4 is a detail sectional view taken on the line 4—4 of Figure 3.

Figure 5 is a detail sectional view taken on the line 5—5 of Figure 3.

Figure 6 is a detail sectional view taken on the line 6—6 of Figure 3.

Figure 7 is a detail sectional view taken on the line 7—7 of Figure 3.

Figure 8 is a fragmentary detail sectional view illustrating a trigger ratchet, a holding ratchet and a release for the latter.

Figure 9 is a side elevation illustrating a modified form of my invention.

Figure 10 is a transverse sectional view illustrating the pressure rollers of the modified form of the invention and the operating means therefor and taken on line 10—10 of Figure 9.

Figure 11 is a sectional view taken on the line 11—11 of Figure 9.

Figure 12 is a fragmentary sectional view illustrating one of the dogs of the trigger mechanism for the actuation of the pressure rollers in the modified form of the invention.

Figure 13 is a detail sectional view taken on the line 13—13 of Figure 1.

Figure 14 is a sectional view taken on the line 14—14 of Figure 13.

Figure 15 is a fragmentary side elevation, partly in section, illustrating another modified form of my invention.

Figure 16 is a fragmentary vertical sectional view illustrating the trigger mechanism for the modified form of the invention shown in Figure 15.

Figure 17 is a view similar to Figure 16, showing the trigger mechanism released or in an inoperative position.

Referring in detail to the drawings, the numeral 5 indicates as an entirety a supporting frame of the device, which consists of spaced side walls 6, a bottom wall 7 and a top wall 8. The bottom wall 7 protrudes beyond the vertical rear edges of the side walls 6 and has secured thereto a handle 9, similar in shape to a pistol grip or handle to which is connected a suspension bail 10 whereby the device may be hung on a support when not in use.

A shaft 11 is journaled in the side walls 6 of the frame 5 and has secured thereon a lower pressure roller 12 and gears 13 arranged at the ends of said roller 12. A shaft 14 extends through openings 15 provided in the side walls 6 above the shaft 11 and the openings 15 are of such a size that the shaft 14 may rotate freely as well as having a limited upward and downward movement and a lateral movement. The shaft 14 has secured thereon an upper pressure roller 16 and gears 17 which are adapted to move into and out of mesh with the gears 13 during the operation of the device.

Grooved type bearings 18 receive the shaft 14 and are secured in any suitable way to depending portions 19 formed on a pressure lever 20 pivoted on the side walls 6 of the frame 5, as shown at 21. The pressure lever 20 is of substantially L shape and is constructed so that a portion thereof operates freely between the side walls 6 of the frame and terminates at one end in a concave shaped thumb piece 22 disposed over the upper end of the handle 9, so that when the latter is gripped by a person the thumb of the hand gripping the handle may engage the thumb piece 22 for placing pressure thereon and thereby bring about a pivotal movement of the pressure lever to move the gears 17 into mesh with the gears 13 and the upper pressure roller in squeezing relation to the lower pressure roller 12. The pressure lever 20 may be swung upwardly as indicated by the arrows in Figure 1 to permit the closed end of a collapsible tube 23 to be easily arranged between the pressure rollers from the front end of the frame 5.

The end 24 of the pressure lever 20 may act as a stop for the pivotal movement of said pressure lever 20 in bringing the gears into mesh and the upper pressure roller in squeezing relation with the lower pressure roller by engaging

the under face of the top wall 8 of the frame 5. However, the stop will permit movement of the pressure lever in the direction stated sufficient to bring the gears in mesh and the upper pressure roller in squeezing relation to the lower pressure roller.

The pressure rollers being connected when in squeezing position by the gears will cause said rollers to rotate in opposite directions to each other when one of the rollers is rotated by a trigger mechanism 25, which will be hereinafter more fully described.

In order that the tube 23 be supported in operative position as shown in Figure 1, a self-adjusting support 26 is provided. The support 26 includes a rod 27 slidably mounted in a bearing 28 carried by the top wall 8 of the frame 5. The rod 27 has an offset forked portion 29 that enters openings in an adjustable clamp 30. The forked end of the rod 27 may be secured to the clamp 30 in any well known manner.

The clamp consists of a forked body 31 in which is slidably mounted a bearing member 32 engaged by a feed stem 33 threaded in the body 31. The bearing member 32 includes an arcuately curved head 34 provided with apertured ears 35. The head 34 engages the discharge neck 36 of the collapsible tube 23. A flexible loop element 37 is passed through the apertured ears 35 and about the neck 36 to cooperate with the head 34 in securing the neck to the clamp 30. The ends of the flexible element extend through openings provided in the body 31 and have the free ends enlarged, as shown at 38, to prevent the withdrawing of the flexible element from the body.

Thus it will be seen by manipulating the feed screw 33 the bearing member 32 and flexible element 37 may be made to grip and release the neck 36 of the tube 23. Further, it will be seen that as the collapsible tube is drawn between the pressure rollers by the rotation thereof in opposite directions, the support 26 may move on the frame 5 to permit the movement of the collapsible tube toward said rollers as it is squeezed thereby.

The bearings 18 may have their movements guided by guides 40 secured on the side walls 6 of the frame 5, as shown in Figure 7. The shaft 14 has one end squared, as shown at 41, to permit a key or finger piece 42 to be applied and removed therefrom. The purpose of the finger piece or key 42 is to permit rotation of the pressure rollers in a reverse direction from that indicated by the arrows in Figure 1 for the purpose of moving a compressed tube from said rollers after a complete squeezing operation has been had on the tube or the contents thereof has been fully discharged. Also the key or finger piece 42 may be employed for rotating the rollers in the direction as indicated by the arrows for squeezing the tube should it be desired to so operate the device and not employ the trigger mechanism 25.

The bottom wall 7 forwardly of the handle 9 has formed thereon pairs of depending walls 43. One wall of each pair of walls 43 has portions struck therefrom to form spring seats 44 on which are seated coil springs 45 acting to urge holding ratchets 46 in engagement with the teeth of the gears 15 to prevent the pressure rollers from rotating in a direction reverse from the direction indicated by the arrows in Figure 1. The holding ratchets 46 are slidably mounted between the pairs of depending walls 43 and are provided with teeth 47 to engage the teeth of the gears 13. In order to move the holding ratchets 46 out of engagement with the gears 13, finger

pieces 48 are secured thereto and are arranged exteriorly of the pairs of walls 43. The finger pieces 48 are connected to the holding ratchets by pins 49 operating in slots provided in the outermost walls of the pairs of walls 43. The finger pieces 48 are flexible and are provided with openings 50 to receive the ends of a trigger shaft 51 journaled in the pairs of walls 43. When the finger pieces are brought so as to receive the ends of the trigger shaft, the holding ratchets 46 are held out of engagement with the teeth of the gears 13, freeing the rollers for reverse rotation from that indicated by the arrows in Figure 1.

Trigger ratchets 54 including spring influenced dogs 55 are secured on the trigger shaft 51 and are adapted to rotate the gears 13 in the direction indicated by the arrows in Figure 5 and also in Figure 1, when the trigger shaft 51 is rotated in one direction. The dogs 55 may ratchet relative to the gears 13 when moving in a reverse direction. A trigger 58 is secured on the trigger shaft 51 and has connected thereto a trigger retracting spring 59 so as to return the trigger to a neutral position when manually released. The trigger ratchets 54 are spring influenced in one direction by leaf springs 60 secured on the depending walls 43 and when the trigger is pulled by the operator, the movements of the trigger ratchets 54 are limited by stops 61 carried by the depending walls 43.

In operation, with a collapsible tube applied to the device, as shown in Figure 1, the operator grasps the handle 9 in one hand and with the thumb of said hand pressing on the finger pieces 22 of the pressure lever the pressure rollers are caused to assume squeezing position on the tube with the gears 13 and 17 in mesh. A pull on the trigger 58 by the operator will impart rotation to the pressure rollers, squeezing the tube so as to dispense the contents therefrom. The operator may continue to operate the trigger by the finger in a trigger motion and thereby intermittently discharge the contents of the tube. When it is desired to remove a squeezed or empty tube from the device, the finger pieces 48 are brought into position of the ends of the shaft 51 entering the openings thereof, thus retracting the holding ratchets 46 from the gears 13. The pressure on the thumb piece of the lever 20 is released and the latter may be swung upwardly as indicated by the arrows in Figure 1 moving the upper pressure roller away from the lower pressure roller so that the empty tube may be withdrawn from between the rollers and then detached from the supporting device 26 when another tube may be applied to the device.

A device of this kind will be extremely easy to handle and operate and permits a person to readily direct the intermittent discharging of the contents of the tube onto a surface by simply actuating the trigger as many times as desired. This mode of operation will assure complete emptying of the tube of its contents and also will assure against waste of the contents, and further when the device is not in use it may be readily placed in a suspended position on a support by engaging the bail 10 therewith.

Referring to my modified form of invention as shown in Figures 9 to 12, inclusive, the frame 5, hand grip 9, tube supporting means 26 and upper and lower pressure rollers 16 and 12 are employed with the connecting gears 13 and 17. In this form of the invention, the shafts of the pressure rollers 12 and 16 are indicated by the characters 62 and 63 journaled in the side walls 6

of the frame 5. However, the shaft 63 may slide vertically as well as being rotatable. The shaft 63 is shaped to receive the key or finger piece 42. Both the shafts 62 and 63 are grooved to receive tensioning devices 64, each consisting of loop shaped elements 65 to engage in the grooves of the shafts and an operating lever 66 to which the loop shaped elements 65 are pivoted. The pivotal connections between the lever 66 and loop shaped elements is such that when the lever 66 is in one position, the loop shaped elements are moved apart and when in another position are brought toward each other. This will permit the pressure roller 16 to be drawn toward the pressure roller 12 and released therefrom when desired. As for instance, when inserting the closed end of the tube between said pressure rollers the lever 66 may be positioned so that the pressure roller 16 may move upwardly.

A trigger carriage is slidably mounted between the side walls 6 of the frame 5 on the bottom wall 8, the connections between the side walls and bottom wall 8 in this instance being offset to form channels to receive the longitudinal guides for the carriage.

Spring pressed holding dogs 68 are pivotally mounted on the carriage to engage with the gears 13 of the pressure roller 12 to prevent a reverse rotation of the lower pressure roller. The carriage is mounted for sliding movement backward and forward and is spring influenced in one direction by a spring 69 connected thereto. A trigger 70 is pivotally mounted on the bottom wall and has a pin and slot connection 72 with the carriage. By operating the trigger 70, the carriage may be caused to move backwardly and forwardly and thereby intermittently rotate the pressure rollers for the purpose of squeezing the tube intermittently to discharge the contents therefrom.

An additional operating means is provided for the rotation of the pressure rollers and consists of a lever 73 constructed similarly to the lever 20 with the thumb piece thereof disposed over the handle 9, as clearly shown in Figure 9. The lever 73 is pivotally mounted on the frame 5 and as shown at 74, and the pivot thereof carries a spring element 75, one end of which bears against the top wall of the frame 5 and the other end against the lever 73. Dogs 76 are pivoted to the lever 73 and engage with the gears 13 of the lower pressure roller. Springs 77 act to hold the dogs 76 in engagement with the gears of the lower pressure roller and will permit said dogs to ratchet thereover during the movement of the lever 73 in one direction. The movement of the lever under thumb pressure in an opposite direction, will assist in rotating the pressure rollers.

Thus it will be seen that the pressure rollers may be operated both by the trigger finger of the hand gripping the handle 9 and by the thumb of said hand operating the lever 73.

The lever 73 is constructed so as to operate exteriorly of the walls 6 of the frame 5.

In Figures 15 to 17, inclusive, a modified form of trigger mechanism is shown. This type of trigger mechanism may be employed in lieu of the trigger mechanism 25 or the trigger arrangement shown in the modified form of my invention shown in Figures 9 to 12, inclusive.

The trigger mechanism shown in Figures 15 to 17, inclusive, consists of depending ears 80 formed on the bottom wall of the frame 5 and

rotatably supports a shaft 81 to which gears 82 are secured. The gears 82 mesh with the gears of the lower pressure roller.

A trigger 82' is journaled on the shaft 81 and has pivoted thereto spring influenced dogs 83 and 84 which engage a ratchet gear 85 secured on the shaft 81. The engagement of the dogs 83 and 84 with the ratchet gear 85 is opposite to each other. The dog 84 is for the purpose of holding the ratchet gear in a reverse rotation, while the dog 83 is employed for imparting a step by step movement to the ratchet gear 85 on the actuation of the trigger. A suitable stop 86 is carried by the trigger 82' for limiting the movement of the trigger 82' by contacting the frame 5.

In order to lock the dogs 83 and 84 out of engagement with the ratchet gear, a hand lever 90 is pivoted to the dog 84 and is provided with an opening 91 which may receive the notched end of the dog 83. When the dogs 84 and 83 are thus connected they are held out of engagement with the ratchet gear freeing the pressure rollers for reverse rotation.

While I have shown and described the preferred embodiment of my invention, it will be understood that minor changes in construction, combination and arrangement of parts may be made without departing from the spirit and scope of the invention as claimed.

Having thus described the invention, what I claim is:

1. A tube squeezer, a frame, tube squeezing rollers carried by said frame and one of said rollers mounted in the frame for adjustment relative to the other roller, means for adjusting the rollers relative to each other, a trigger shaft journaled on the frame, a pistol type hand grip secured to the frame, means connecting said shaft to one of said gears, a ratchet gear secured on said shaft, a trigger journaled on the shaft, dogs pivoted on said trigger and engaging the ratchet gear in opposite directions, and one of said dogs acting to hold the shaft against rotation in one direction and the other dog acting to rotate the shaft by the movement of the trigger, and means for securing said dogs free of the ratchet gear.

2. In a tube squeezer, a frame, tube squeezing rollers carried by said frame and one of said rollers mounted in the frame for adjustment relative to the other roller, means for adjusting the rollers relative to each other, a trigger shaft journaled on the frame, a pistol type hand grip secured to the frame, gears connecting said rollers, means connecting said shaft to one of said gears, a ratchet gear secured on said shaft, a spring influenced trigger journaled on said shaft, spring influenced dogs pivoted on said trigger and engaging the ratchet gear in opposite directions, one of said dogs acting to hold the shaft against rotation in one direction and the other dog acting to rotate the shaft by the movement of the trigger, and a lever pivoted to one of the dogs and having an opening to receive the other dog for releasably securing said dogs out of engagement with the ratchet gear.

3. In a tube squeezer, a frame, tube squeezing rollers carried by said frame and one of said rollers mounted in the frame for adjustment relative to the other roller, means for adjusting the rollers relative to each other, a rod slidably connected to the frame, and extending horizontally therefrom, a clamp carried by the rod and

75

gripping a neck of a collapsible tube with the closed end of the latter received between said rollers, a trigger shaft journaled on the frame, a pistol type hand grip secured to the frame, gears connecting said rollers, means connecting said shaft to one of said gears, a ratchet gear secured on said shaft, a spring influenced trigger journaled on the shaft, spring influenced dogs

5 pivoted on said trigger and engaging the ratchet gear in opposite directions, one of said dogs acting to hold the shaft against rotation in one direction and the other dog acting to rotate the shaft by the movement of the trigger, and means for securing said dogs free of the ratchet gear.

BOYCE J. OLIVER.
